UNITED STATES PATENT OFFICE

GEORGE M. HOLLEY, OF DETROIT, MICHIGAN

CARBURETOR-ACCELERATING MEANS

Application filed September 1, 1927. Serial No. 216,830.

The object of this invention is to improve the acceleration of an automobile operated by an internal combustion engine, provided with an explosive mixture produced in a carburetor in which a gravity fed fuel nozzle discharges under the influence of the in-drawn air.

Specifically the object of this invention is to provide improved means operated by the carburetor throttle located in the mixture outlet, which will provide the necessary increased fuel supply needed during acceleration, and will automatically regulate the amount so as to provide more fuel when the throttle is opened rapidly, and less when the throttle is opened slowly.

A second object is to provide means whereby the initial movement of the throttle is relatively ineffective to provide the increased fuel supply for acceleration, as compared with the later portion of the throttle movement towards the wide open position.

Figure 1 shows the preferred form of the accelerating device applied to a double Venturi carburetor of a well known type. In order to make the clearest disclosure the parts are shown in one plane in partial sectional elevation.

Figure 2 shows a partial section on plane 2-2 of Figure 1.

Figure 3 shows a slight modification of the same invention disclosed in Figure 1.

Figure 4 shows a partial section on plane 4-4 of Figure 3.

In Figures 1 and 2, A is the air entrance, B is the larger venturi, and C is the smaller discharging into the throat of B in the well known manner. D is the high speed nozzle (unvented) discharging into the throat of C and fed from the float chamber through the passage F. G is the compensating nozzle, also discharging into C and air vented through the restricted opening H, which feeds air from the atmosphere into this nozzle G through plurality of openings J, arranged one above the other.

Gasoline is supplied to G through the passage K, controlled by the needle E. The explosive mixture supply to the engine is controlled by the throttle I, to which is con-

nected a lever L which contacts with the end of the rod M to which is connected the displacer or plunger N, which is provided with ears (like keys) (Fig. 2) which guide it up and down in the cylinder O. A spring P tends to raise the displacer N, so as to keep the upper end of the rod M in contact with the lever L. A non-return valve Q is located in the bottom of the cylinder O. Gasoline is fed to O through the passage R. A passage S is provided communicating with O through the drilled plugs T, for a purpose to be described. A vent U leads air into the enclosed space above the open upper end of the cylinder O. A horizontal passage V located above the level X-X allows fuel displaced by the displacer N to flow into C, being carried along and sprayed by air drawn in at U in a well known manner.

In Figures 3 and 4, the displacer N is provided with a groove or slot W, with which a ball Z engages. This ball serves to keep the groove or slot W in line with the outlet V. A slight spring Y causes the ball to engage with the groove. A low speed fuel nozzle D' is shown independently fed from the fuel reservoir and discharging in advance of the throttle valve into the mixture outlet.

In Figure 1 a low speed nozzle P' is also provided discharging adjacent to and in advance of the lower lip of the butterfly throttle.

Operation.—On opening the throttle suddenly (Figs. 1 and 2) the fuel in O is displaced by the descent of the plunger N and fuel rises above the level of the passage V, through which it issues to the smaller venturi C. Meanwhile air is drawn in through U and the fuel therefor is aspirated as it issues into the throat of the venturi C. When the throttle is opened slowly fuel leaks back into the float chamber through the passage S, which is in communication with O through the restricted outlet T T.

In Figures 3 and 4 similar results are obtained, except that the action is more positive if the throttle is completely opened. The reason for this is that as the displacer or plunger N descends it closes and seals the overflow bypasses T T T, so that the further

(and faster) the displacer N descends the more positively is the fuel discharged into the mixing chamber C, and it is when the throttle is completely opened and opened quickly that the need for extra fuel is most critical.

What I claim is:—

1. In a carburetor having a constant level fuel supply chamber, a fuel nozzle connected thereto, a mixing chamber into which the nozzle discharges, a mixture outlet, a throttle valve therein, means for supplying an additional and temporary fuel supply, comprising a cylinder, a submerged passage connecting said cylinder to said supply chamber, a check valve in said passage, a displacer in said cylinder operated by said throttle so as to descend as the throttle opens, a passage located above the level in said constant level supply chamber connecting said cylinder with said mixing chamber, an atmospheric communication leading to the upper portion of said cylinder through which aspirating air is adapted to flow to said mixing chamber, a bypass located below the level of fuel in said constant level fuel supply chamber and leading from said cylinder back into said constant level chamber, a restriction in said bypass.

2. In a carburetor having a constant level fuel supply chamber, a fuel nozzle connected thereto, a mixing chamber into which the nozzle discharges, a mixture outlet, a throttle valve therein, means for supplying an additional and temporary fuel supply comprising a cylinder, a submerged passage connecting said cylinder to said supply chamber, a check valve in said passage, a displacer in said cylinder operated by said throttle so as to descend as the throttle opens, a passage located above the level in said constant level supply chamber connecting said cylinder with said mixing chamber, an atmospheric communication leading to the upper portion of said cylinder through which aspirating air is adapted to flow to said mixing chamber, a bypass leading to said supply chamber from said cylinder, a restricted passage in said bypass.

3. In a carburetor having a constant level fuel supply chamber, a fuel nozzle connected thereto, a mixing chamber into which the nozzle discharges, a mixture outlet, a throttle valve therein, means for supplying an additional and temporary fuel supply comprising a cylinder, a submerged passage connecting said cylinder to said supply chamber, a check valve in said passage, a displacer in said cylinder operated by said throttle so as to descend as the throttle opens, a passage located above the level in said constant level supply chamber connecting said cylinder with said mixing chamber, an atmospheric communication leading to the upper portion of said cylinder through which aspirating air is adapted to flow to said mixing chamber, a by-

pass leading to said supply chamber from said cylinder through a restricted passage, said displacer being adapted during its operating stroke to obstruct the flow of gasoline through said bypass.

4. In a carburetor having a constant level fuel supply chamber, a fuel nozzle connected thereto, a mixing chamber into which the nozzle discharges, a mixture outlet, a throttle valve therein, means for supplying an additional and temporary fuel supply comprising a cylinder, a submerged passage connecting said cylinder to said supply chamber, a check valve in said passage, a displacer in said cylinder operated by said throttle so as to descend as the throttle opens, a passage located above the level in said constant level supply chamber connecting said cylinder with said mixing chamber, an atmospheric communication leading to the upper portion of said cylinder through which aspirating air is adapted to flow to said mixing chamber, a restricted bypass leading to said supply chamber and connected to said cylinder through a plurality of restricted passages located at different levels below the level in said supply chamber, said displacer being adapted during the operating stroke to successively obstruct the flow of gasoline through said passages.

In testimony whereof I affix my signature.

GEORGE M. HOLLEY.
